UNITED STATES PATENT OFFICE.

HARRY COPLAN, OF NORFOLK, VIRGINIA, ASSIGNOR TO LEVIOLA TALKING MACHINE SALES CORPORATION, A CORPORATION OF VIRGINIA.

DESIGN FOR A PHONOGRAPH-CABINET.

54,531.

Specification for Design.

Patented Mar. 2, 1920.

Application filed July 8, 1919. Serial No. 309,514. Term of patent 14 years.

To all whom it may concern:

Be it known that I, **HARRY COPLAN**, a citizen of the United States, residing at Norfolk, in the county of Norfolk, State of Virginia, have invented a new, original, and ornamental Design for Phonograph-Cabinets, of which the following is a specification, reference being had to the accompanying drawings, forming a part thereof.

The figure of the drawing is a perspective view of a phonograph cabinet with the lid closed showing my design.

My design comprises a cabinet having four corner posts between which extend side portions. One of the side portions, preferably the front, is ornamented by wreath designs. These wreath designs are arranged with one on each side of the lower portion of the

cabinet and with one in substantially the middle of the upper portion of the side, and with a grille-work comprising substantially straight bars supporting the upper wreath. The front portion of the posts, preferably is countersunk to form panels and preferably ornamental medallions are provided on the upper ends of the front of the posts. The top is beaded and provided with a concave molding, and terminates with a flat cover portion.

Having shown and described my invention, what I claim is:

The ornamental design for a phonograph cabinet substantially as shown and described.

HARRY COPLAN.
